UNITED STATES PATENT OFFICE.

LUCIEN LIAIS, OF PARIS, FRANCE.

INVERTED INCANDESCENT GAS OR VAPOR LAMP.

No. 901,628.

Specification of Letters Patent.

Patented Oct. 20, 1908.

Application filed November 30, 1904. Serial No. 234,928.

To all whom it may concern:

Be it known that I, LUCIEN LIAIS, engineer, a citizen of the French Republic, residing at Paris, 19 Rue Cambon, in the Department of the Seine, France, have invented new and useful Improvements in Inverted Incandescent Gas or Vapor Lamps, of which the following is a specification.

This invention relates to incandescent vapor lamps or burners in which may be used coal gas, water gas, and other vapors, and is an improvement upon the invention patented by me August 23rd, 1904, numbered 768,382, for incandescent gas or vapor lamps, and is adapted for use in railway cars, carriage lamps, street lamps, and other employments.

The accompanying drawing shows a view in vertical cross section of the burner, Figure 1. Fig. 2 is a view in plan of the collar, described further on.

The whole of this arrangement consists of an inverted burner 2, of cast aluminium or any other metal which is a good heat conductor, a cone 5 acting as a circular side reflector, a chimney 1, supporting the whole of the burner and a flat annular reflector 11 by means of screws or rivets 14 passing through vertical flanges on the side reflector 30 and extending into the chimney.

At the extremity of the burner is a piece of steatite 6 whose use is to prevent the metallic part of the burner being raised to the melting point.

At the upper part of the burner, is situated an injector 3¹, surmounted by the gas pipe 3. On each side of the burner are disposed air inlet tubes fitted with screw plugs which fit tightly to prevent them shaking loose through vibration. These stop screws are hollowed and provided with a lateral hole 4, so as to regulate the air admission.

The lower part of the conical reflector 5, is fitted with a collar of metal, 12, secured to the reflector by an arm 13, which collar acting as a spring is kept closed by means of a thumb screw 10, passing through the two lugs 14; the object of this collar is to hold the globe or casing 8 which is fitted to carry the mantle 7 by arms 15. This mantle is mounted upon a metallic socket which fits into the glass globe, so that when handled, the mantle is constantly kept free from injuries.

The bottom of the globe or casing 8 is pro-

vided with a hole 9 to admit the air required for combustion.

The whole combination as described works as follows:—The gas passing through the injector 3¹, mixes with the air admitted through the lateral holes of the hollow stop screws, the mixture hence comes inside the mantle 5, where it is burned, the air necessary to the combustion is admitted through the aperture 9 in the globe bottom; and the products of combustion pass inside the conical reflector 5 and from there into the cap of the lamp through the chimney 1, as shown on the drawing by the arrows.

It will be seen that the hollow reflector 5 forms a portion of the flue through which the products of combustion escape and that it also constitutes an imperforate connection between the globe or casing 8 and the chimney 1. The said reflector and casing may thus be said to form continuations of said chimney, as they complete the flue for the escape of the products of combustion down to and below the mantle 7. By this construction a supply of air is drawn in by suction through the opening 9 in the globe or casing 8, and all of the products of combustion are forced to pass out through the chimney 1 and to effect a regeneration of the gas or vapor flowing to the burner 2. Besides, the hot gas or vapor, at the point of its ignition at the burner, is brought into intimate contact with the mantle or filament 7, serving to maintain it at an even and continuous state of incandescence.

The advantages of the globe or casing 8 are:—If the mantle breaks through vibration, it falls into the globe, but as this globe is of small size, the mantle always keeps in contact with the flame of the burner, so that the light shall never be completely out. Moreover, the mantle being constantly protected by the globe, it cannot be either spoiled or broken during the putting of it into its place.

Having now described my invention what I desire to claim is:—

1. In an inverted incandescent burner, a depending tube, a filament supported around the lower end thereof, and a hollow conical reflector leading from the upper end of said filament and forming part of a flue through which the products of combustion escape.

2. In an inverted incandescent burner, a depending burner, a filament supported around said burner, a hollow conical re-

- 5 reflector leading from the upper end of said filament and forming part of a flue through which the products of combustion escape, and a transparent casing surrounding said filament and leading downwardly from the lower end of said reflector.
- 10 3. In an inverted incandescent burner, a depending burner, a filament supported around said burner, a hollow conical reflector leading from the upper end of said filament and forming part of a flue through which the products of combustion escape, and a transparent casing surrounding said filament and depending from the reflector.
- 15 4. In an inverted incandescent burner, a

depending tube, a filament supported around the lower end thereof, a hollow conical reflector through which the products of combustion escape, and a transparent casing depending from said reflector and surrounding said filament so as to direct the products of combustion into contact with said filament and through said hollow reflector. 20

In testimony whereof I have signed my name to this specification in the presence of 25 two subscribing witnesses.

LUCIEN LIAIS.
